UNITED STATES PATENT OFFICE.

GEORGE EDWIN WASHINGTON AND HAROLD WASHINGTON, OF MANCHESTER,
ENGLAND.

AUDIBLE ALARM OR INDICATION APPARATUS.

1,400,113.

Specification of Letters Patent.

Patented Dec. 13, 1921.

Application filed June 25, 1919. Serial No. 306,732.

To all whom it may concern:

Be it known that we, GEORGE E. WASHINGTON and HAROLD WASHINGTON, subjects of the King of Great Britain and Ireland, and residents of Manchester, in the county of Lancaster, England, have invented a certain new or Improved Audible Alarm or Indication Apparatus, (for which we have filed an application in Great Britain on June 10 1918, Patent No. 120,182,) of which the following is a specification.

This invention relates to an improved device for use in offices and other places where it may prove useful, of that type for giving 15 an audible alarm at any predetermined times, mainly to indicate that a certain act or acts should be performed by some person within sound of the alarm, the act or acts to be performed being noted on a paper 20 strip, card or other suitable medium. As examples it may be that some one is to be telephoned to at a particular time, that some 25 appointment should be kept at the time, that some step in a process of manufacture must be arrested or commenced at the time of the 30 alarm; for automatically controlling time tables in schools and so on with an almost infinite number of acts which will be readily understood.

To the aforesaid end our invention comprises improved means to indicate the character of the act to be done, intermediate 35 gearing connected with the clock mechanism for causing a movable arm separate from the clock mechanism at a predetermined time or times either to close an electric circuit and give an audible electrical alarm, or to give a mechanically operated audible alarm, means to allow the arm to be 40 set to the correct time of day at the initial stage and means for stopping the clock at the end of the day.

Our invention will be fully described with reference to the accompanying drawings 45 which show by way of example an apparatus constructed in accordance with our invention and in which,

Figure 1, is a side elevation, partly in section, of an apparatus for giving an electrical alarm,

Fig. 2, plan of same with the cover removed,

Fig. 3, end elevation, partly in section,

Fig. 4, plan with cover in position,

55 Figs. 5 and 6, plan and side elevation, re-

spectively, of an operating arm arranged to give a mechanical alarm,

Figs. 7 and 8 and Figs. 9 and 10 similar views to Figs. 5 and 6 of modified forms of arms for giving a mechanical alarm,

Fig. 11, side elevation of a modified form of the arrangement shown in Figs. 1 to 3 for driving the indicating arm,

Fig. 12, plan of same,

Fig. 13, sectional elevation of a modified 65 construction of the upper end of the indicating arm,

Fig. 14, side and front elevation, respectively, of a modified form of contact device on the indicating arm,

Fig. 15, diagram of electrical connections,

Fig. 16, modified form of indicating arm as applied to the flat type of machine shown in Fig. 18,

Fig. 17, plan of Fig. 16, and

Fig. 18 perspective view of a flat type of machine.

In all foregoing figures similar reference characters indicate corresponding parts.

In accordance with our invention we provide a strip of cardboard, paper or other suitable medium *a* of any required length and width, marked at the side, as in the column *b* the time of the day from say 8 o'clock a. m. to 7 o'clock p. m. in quarter 80 hour or other sub-divisions. The bulk of the paper surface is for memoranda of the acts to be performed at predetermined times. One strip may be provided for every day and be suitably dated for noting calls in the 85 future. This strip is held in position by suitable clips *c* on the cover *d* of the apparatus. A package of strips *a* bearing daily 90 dates may be held in position upon a wooden or other base *e* or holder removably secured 95 to the cover or frame of the apparatus so that daily memoranda may be written in readiness to place on the cover of the apparatus.

The apparatus with particular reference 100 to Figs. 1 to 3 comprises a base *f* for supporting the operative mechanism which is inclosed by the removable cover *d*. The latter is graduated at *g* to correspond with the division of time on strip *a* and is further provided with a slot *h* through which projects the operating or indicating arm *i* hereinafter 105 more particularly referred to. In addition the cover has holes *j* for the reception of metal pegs *k* which can be placed in such 110

holes opposite any time mark or marks as required by the memoranda or strip *a*. A supply of pegs may be kept in holes *m*. The mechanism to be now described is for moving the arm *i* through the arc of a circle to close an electric circuit and sound the alarm. The means comprise ordinary clockwork mechanism in case *n*, the main shaft *o* of which drives through suitable gear *p*, including a wheel *s* freely mounted upon a fixed shaft *q*, which carries a friction disk *r*, pressed against the wheel *s* of the gear train referred to by a second disk *t* controlled by compression spring *u*. The disk *t* has secured to it the arm *i* so that such arm is moved around by the clock to indicate the time of day. The arm *i* carries a flexible arm *v* adapted to contact with the pegs *k* as the main arm *i* moves forward and so complete a circuit in which is included the battery *w* and electric bell *x*. *y* is the hammer of the bell. The various parts of the alarm mechanism are coupled by wires 2, to complete the circuit. The bell rings continuously while the flexible arm *v* passes the first peg *k*, the indicating arm meanwhile passing forward toward any other succeeding peg *k*. When the flexible arm clears the first peg the bell ceases to ring. The flexible arm may be replaced by a weighted arm or tumbler catch carried by arm *i*.

In Figs. 11 and 12 the wheel *p* is made as a crown wheel and is driven direct by pinion *o*.

35 The use of the friction disk connection described enables the arm *i* to be set along the slot in the cover of the time of day without affecting the ordinary clockwork mechanism. The arm may return to the initial position 40 without removing the pegs, if desired.

To stop the clock at the end of the day, the disk *t* has a projecting arm adapted to contact with and lift a spring or pivoted arm 4 into the path of an arm 5 carried by 45 the rotating clock shaft 6.

In Figs. 5 and 6 we have shown mechanical means of giving an audible alarm. Herein we employ in connection with arm *i* and carried by it in a bearing 7 a rod 8 fitted 50 with a shoe 9. The inner end of the arm is coupled to the pivoted striking arm 10 connected with a special gong or bell 11. A spring 12 normally presses rod 8 outwardly so that when the shoe 9 contacts with pegs 55 *k* the gong or bell is struck and an audible alarm given.

Figs. 7 and 8 show a somewhat similar arrangement to that in Figs. 5 and 6 in which the inner end of rod 8 is arranged to strike 60 a bell 11 carried by the arm *i*.

Figs. 9 and 10 indicate a modification of the arrangement shown in Figs. 7 and 8, in which the rod 8 is turned about its axis when contacting pegs *k* to strike the gong 11.

65 In Fig. 13 we have shown the upper end

of the indicating arm *i*, provided with a tip 13 made of colored fiber or like material primarily to insulate the end of the arm *i* and incidentally to form a conspicuous indicator. The tip would be made to simply 70 push tightly on to the arm *i* and may or may not be fitted with a cushion spring 14 so as to eliminate the possibility of damage.

Fig. 14, shows a still further modification 75 of contact device for the arm *i*. This arrangement is designed to break the circuit while wire is still against the peg *k* and so prevent wastage by bell ringing for an unduly long period. It consists of a spring contact 80 bar 15 insulated from the arm *i* at 16 making contact only at point 17, 18 is the wire to make contact with peg *k* and being in the form of a spiral spring will make contact and ring the bell. The forward movement of the arm *i* will separate the points at 17 85 and break the circuit. Plate 19 will restrain the movement of the bar 15 and eventually cause wire 18 to slip off the peg *k*.

Fig. 18 shows a flat type of machine in which the controlling mechanism is the same 90 as in that already described. The principal difference is that means are provided to give a straight path to the indicating arm which consists of a short arm 20 passing through the slot *h*, such arm being freely mounted 95 upon a pin 21 supported upon an extension 22 of a rod 23. The arm 20 is counter-weighted at its lower end. The rod 23 is fixed in a block 24 mounted freely upon the end 25 of the arm 26 fixed to the disk *t*. The 100 rod 23 is extended beyond the block and is yoked by a spring 27 to the lower end of the arm 26, while its forward end carries a fiber insulating roller 28 bearing against the underside of the casing *d* as a result of the action of the spring 27. A weight may be used in place of the spring. As the disk *t* rotates the indicating arm 20 is drawn along the slot *h* to contact the pins *k* as in the manner before described. 110

In Fig. 18, the casing of the flat type of machine is provided with a well 29 to receive a block or pad of paper strips *a* sufficient to last, say, for a month, though the casing may be left without the well and a single strip *a* be used at a time as in the first machine described.

In some cases we provide an additional bell to be rung in another room. Fig. 15 shows in diagram form an electric circuit arranged to give this. In this diagram 30 is the machine, 31 a switchboard that can be placed in any suitable position, 32 the battery for the machine bell and 33 the battery for the additional bell 34. 35 represents a removable plug. 36 is a bell push for ringing the additional bell by hand when required.

The machine may be fitted so as to be controlled by a master clock, such clock con- 130

trolling any number of machines in one establishment.

The indicating arm *i* may likewise be arranged to automatically break the electrical circuit on the arm reaching the end of the slot *h* and so prevent possibility of leakage when the machine is not in use. The tip of the arm *i* may also be a little below the surface of the machine cover and the slot *h* 10 be covered with a transparent panel of glass or other material to exclude dust from the interior of the machine.

What we claim and desire to secure by Letters Patent is:—

- 15 1. In an audible alarm, a base, a cover plate secured to the base and provided with a slot, a removable memorandum card marked to indicate time and attached to the cover at one side of the slot, a shaft secured 20 to the base and arranged under the cover plate, an oscillatory arm pivoted on the said shaft and projecting through the said slot, means for sounding an audible alarm when the arm arrives at predetermined markings 25 on the time card, and a clockwork mechanism secured to the base and operatively connected with the said arm.
2. In an audible alarm, a base, a cover plate secured to the base and provided with 30 a slot and a row of holes arranged adjacent to the slot, a shaft secured to the base and arranged under the cover plate, an oscillatory arm pivoted on the said shaft and pro-

jecting through the said slot, removable pegs inserted in the said holes, a flexible contact member attached to the said arm and engaging with the pegs one after another, means for sounding an audible alarm when the said contact member is in engagement with any one of the said pegs, and a clock-work mechanism secured to the base and operatively connected with the said arm. 35 40

3. In an audible alarm, a base, a cover plate secured to the base and provided with a slot, a shaft secured to the base and arranged under the cover plate, a driving wheel journaled on the said shaft, a clock-work mechanism secured to the base and operating to revolve the said wheel, a disk journaled on the said shaft, an arm secured 50 to the said disk and projecting through the said slot, a friction disk interposed between the said disk and wheel, and a spring holding the friction disk in driving engagement with the said disk and wheel and permitting the 55 said arm to be moved back and forth by hand in the slot to set it.

In testimony whereof we have hereunto set our hands in the presence of two witnesses.

GEORGE EDWIN WASHINGTON.
HAROLD WASHINGTON.
